US00D982853S

(12) **United States Design Patent** (10) **Patent No.:** **US D982,853 S**
(45) **Date of Patent:** **** Apr. 4, 2023**

(54) **OUTDOOR CAT TOWER**

(71) Applicant: **Shaoming Huang**, Nanchang (CN)

(72) Inventor: **Shaoming Huang**, Nanchang (CN)

(73) Assignee: **Shaoming Huang**, Nanchang (CN)

(**) Term: **15 Years**

(21) Appl. No.: **29/851,942**

(22) Filed: **Sep. 1, 2022**

Related U.S. Application Data

(63) Continuation-in-part of application No. 29/804,901, filed on Aug. 23, 2021, now Pat. No. Des. 971,526.
